UNITED STATES PATENT OFFICE.

JAMES A. MURPHEY, OF GERMANTOWN, PENNSYLVANIA.

MEANS FOR WAY-BILLING.

1,086,203.

Specification of Letters Patent.

Patented Feb. 3, 1914.

Application filed July 12, 1912. Serial No. 708,973.

To all whom it may concern:

Be it known that I, JAMES A. MURPHEY, of Germantown, in the State of Pennsylvania, have invented a certain new and useful Improvement in Means for Way-Billing, whereof the following is a specification, reference being had to the accompanying drawing.

My improvement is particularly applicable to systems of way-billing packages for shipment by express, to insure accuracy in determining the proper rates of charges for goods of different descriptions, and the proper amount of charges for individual shipments.

It is the prior practice to have a "caller" read from each package the name of the shipper and addressee to a "writer" who makes out the way-bill, and said "writer" is supposed to refer to a tariff schedule where-in the rates for transportation from the place of shipment to other places are set forth. However, different rates are charged, for transportation to any given place, in accordance with the different classes of goods transported. For instance, Adams Express Company charges fifty different rates of expressage, ranging from forty cents to twenty dollars per hundred pounds, in accordance with the classification of the goods transported, and, numerous errors of overcharges or undercharges are made by employees who rely upon recollection and make charges in the way-bills without referring to the tariff schedules aforesaid.

It is an object of my invention to obviate such errors, and, also prevent intentional overcharges by dishonest employees, by providing several devices which are co-operatively employed in accordance with my invention as follows:—First, a printed form constituting a tariff distinguishing goods for transportation in respective classes, showing the different rates applicable to those classes, with reference to transportation between different places, and, distinctively indicating different labels to be respectively used on goods in accordance with the rate charged for transportation of the same. Second, a printed form constituting a way-bill having appropriately designated spaces for matter relating to respective shipments, including the weight of each shipment, the class of label and the rate of charge and amount of charge applicable to each shipment; and, third, a series of separable adhesive labels applicable

to the respective shipments distinctively classified and designated in accordance with said tariff, with reference to the rate of charge, and individually distinctively numbered in correspondence with numbers on said way-bill designating the respective shipments; each of said labels having printed thereon the rate for different weights of shipments of the class to which the label relates, and having appropriately designated spaces for matter indicating the date of shipment, whether the charge for shipment has been advanced, is to be collected, or has been paid.

My invention includes the various novel features of construction and arrangement hereinafter more definitely specified.

In the drawing, Figure I shows a printed form of way-bill for a plurality of shipments, having thereon a schedule of charges for different weights of shipments at one rate corresponding with the tariff aforesaid, and, appropriately designated spaces for entries relating to respective shipments. Fig. II shows a series of labels of the same rate class; each having thereon a schedule of charges for different weights of shipments of the class to which the label relates, corresponding with the tariff aforesaid, each of said labels being distinctively numbered in correspondence with the numbers on said way-bill designating the respective shipments, and provided with adhesive A. Fig. III shows a printed form constituting a tariff distinguishing goods for transportation in respective classes, showing different rates applicable to respective classes, with reference to transportation between different places, and distinctively indicating different labels to be respectively used on goods in accordance with the rate charged for transportation of the same.

I find it convenient to distinguish the different classes of labels by class number, for instance, labels for goods for which the express rate is forty cents would be number 1; labels for goods for which the rate is fifty cents would be number 2; labels for goods for which the rate is sixty cents would be number 3, and so on. Accordingly, the classification tariff schedules indicate the rate per hundred pounds opposite the name of the office to which the intended shipment is destined and also indicate the number of the label; 1, 2, 3, 4, or 5, as the case may be, and, each label states on its face the rate per hun-

dred pounds and the charges for shipments of lesser weight.

Way-billing in accordance with my invention is conveniently effected as follows:—

- 5 The way-bill "writer" announces to the "caller" the class of label applicable to a given package; the "caller" takes a label of the class required, for instance a "Label No. 2" such as shown in Fig. II, having printed thereon a statement to the effect that the rate per hundred pounds for transportation of the goods to which it is applied is fifty cents, and a schedule of rates for shipments of lesser weight. Thereupon, the "caller" announces to the "writer" the shipment number which appears on the selected label, for instance, "E-15," the name of the shipper and addressee, the destination of the package, the weight of the package and the proper charge for transportation of the same; which matter is entered in the way-bill. The date of shipment and the amount of charge for the same is also entered on the label in appropriately designated spaces; such spaces for the charge indicating whether it has been paid in advance, is to be collected, or is paid. It may be observed that the label E-15 shown in Fig. II indicates that the package to which it is applicable was shipped February 14, 1912, weighs between forty-six and fifty pounds and that forty-five cents expressage is to be collected.

It may be observed that in accordance with the prior practice, upon receipt of a package at the express office to which it is consigned, a clerk must refer to a way-bill including data with reference to forty packages to ascertain what if any charge to make for the given package. Such reference requires the clerk to scan practically all of the forty entries in the way-bill to select the information regarding each package. Such a system not only necessitates expenditure of much time and labor, but affords opportunities for numerous errors which may be due to failures of the "caller" and "writer" to hear each other, or to the checking clerks failing to hear each other or to mismarking either the package or the way-bill. On the contrary, in accordance with my invention each shipment carries on its label, the information contained in the tariff classification, essential to not only enable the agent at the place of delivery to make the charges and entries independently of the way-bill; thus saving the time and labor now required to refer to the way-bill for such information for each shipment, but, also enabling such agent and the consignee to determine whether the proper charge has been made.

I do not desire to limit myself to the precise details of construction and arrangement herein described as various modifications may be made therein without departing from

the essential features of my invention as defined in the appended claims.

I claim:—

1. Means for way-billing express shipments, including a printed form constituting a tariff distinguishing goods for transportation in respective classes, showing the different rates applicable to those classes, with reference to transportation between different places, and, distinctively indicating the different labels to be respectively used on goods in accordance with the rate charged for transportation of the same; a printed form constituting a way-bill having appropriately designated spaces for matter relating to respective shipments, including the weight of each shipment, the class of label and the rate of charge and amount of charge applicable to each shipment; and, series of separable adhesive labels applicable to the respective shipments, distinctively classified and designated in accordance with the rate of charge and individually distinctively numbered in correspondence with numbers on said way-bill designating the respective shipments; each of said labels having printed thereon the rate for different weights of shipments of the class to which the label relates, and, having appropriately designated spaces for matter indicating the date of shipment, whether the charge for shipment has been advanced, is to be collected, or has been paid.

2. Means for way-billing express shipments, including a printed form constituting a tariff distinguishing goods for transportation in respective classes, showing the different rates applicable to those classes, with reference to transportation between different places, and, distinctively indicating the different labels to be respectively used on goods in accordance with the rate charged for transportation of the same; a printed form constituting a way-bill having appropriately designated spaces for matter relating to respective shipments, including the weight of each shipment, the class of label and the rate of charge and amount of charge applicable to each shipment; and, series of separable adhesive labels applicable to the respective shipments, distinctively classified and designated in accordance with the rate of charge and individually distinctively numbered in correspondence with numbers on said way-bill designating the respective shipments; each of said labels having printed thereon the rate for different weights of shipments of the class to which the label relates, and, having appropriately designated spaces for matter concerning the shipment to which it relates.

3. Means for way-billing express shipments, including a printed form constituting a tariff distinguishing goods for trans-

portation in respective classes, showing the different rates applicable to those classes, with reference to transportation between different places, and, distinctively indicating different labels to be respectively used on goods in accordance with the rate charged for transportation of the same; a printed form constituting a way-bill having appropriately designated spaces for matter relating to respective shipments including the weight of each shipment and the class of label applicable to each shipment; and, series of separable adhesive labels applicable to the respective shipments, distinctively classified and designated in accordance with the rate of charge and individually distinctively numbered in correspondence with numbers on said way-bill designating the respective shipments, each of said labels having printed thereon the rate for different weights of shipments of the class to which the label relates.

4. Means for way-billing express shipments, including a printed form constituting a tariff distinguishing goods for transportation in respective classes, showing the different rates applicable to those classes, with reference to transportation between different places, and, distinctively indicating different labels to be respectively used on goods in accordance with the rate charged for transportation of the same; a printed form constituting a way-bill having appropriately designated spaces for matter relating to respective shipments including the weight of each shipment and the class of label applicable to each shipment; and, series of separable adhesive labels applicable to the respective shipments, distinctively classified and designated in accordance with the rate of charge and individually distinctively numbered in correspondence with numbers on said way-bill designating the respective shipments.

45 5. Meáns for way-billing express shipments, including a printed form constituting a tariff distinguishing goods for transportation in respective classes, showing the different rates applicable to those classes,
50 with reference to transportation between different places, and, distinctively indicating different labels to be respectively used on goods in accordance with the rate charged for transportation of the same;
55 and, a printed form constituting a way-bill having appropriately designated spaces for matter relating to respective shipments including the weight of each shipment and the class of label applicable to each shipment.

6. Means for way-billing express shipments, including a printed form constituting a tariff distinguishing goods for transportation in respective classes, showing the dif-

ferent rates applicable to those classes, with reference to transportation between different places, and, distinctively indicating different labels to be respectively used on goods in accordance with the rate charged for transportation of the same. 70

7. Means for way-billing express shipments, including a printed form constituting a way-bill having appropriately designated spaces for matter relating to respective shipments, including the weight of each shipment, the class of label and the rate of charge and amount of charge applicable to each shipment; and, series of separable adhesive labels applicable to the respective shipments, distinctively classified and designated in accordance with the rate of charge and individually distinctively numbered in correspondence with numbers on said way-bill designating the respective shipments; each of said labels having printed thereon the rate for different weights of shipments of the class to which the label relates, and, having appropriately designated spaces for matter indicating the date of shipment, whether the charge for shipment has been advanced, is to be collected, or has been paid.

8. Means for way-billing express shipments, including a printed form constituting a way-bill having appropriately designated 95 spaces for matter relating to respective shipments, including the weight of each shipment, the class of label and the rate of charge and amount of charge applicable to each shipment; and, series of separable 100 adhesive labels applicable to the respective shipments, distinctively classified and designated in accordance with the rate of charge and individually distinctively numbered in correspondence with numbers on said way- 105 bill designating the respective shipments, each of said labels having printed thereon the rate for different weights of shipments of the class to which the label relates.

9. Means for way-billing express shipments, including a printed form constituting a way-bill having appropriately designated spaces for matter relating to respective shipments, including the weight of each shipment, the class of label and the rate of charge and amount of charge applicable to each shipment. 110 115

10. Means for way-billing express shipments, including a way-bill having distinctively numbered spaces for entries designating the respective shipments, and series of separable adhesive labels applicable to respective shipments, distinctively classified and designated in accordance with the rate of charge and individually distinctively numbered in correspondence with numbers on the way-bill designating the respective shipments; each of said labels having print- 120 125

ed thereon the rate for different weights of shipments of the class to which the label relates, and, having appropriately designated spaces for matter indicating the date of shipment, whether the charge for shipment has been advanced, is to be collected, or has been paid.

11. Means for way-billing express shipments, including a way-bill having distinctively numbered spaces for entries designating the respective shipments, and series of separable adhesive labels applicable to respective shipments, distinctively classified and designated in accordance with the rate of charge and individually distinctively numbered in correspondence with numbers on the way-bill designating the respective shipments; each of said labels having printed thereon the rate for different 20 weights of shipments of the class to which the label relates, and, having appropriately

designated spaces for matter concerning the shipment to which it relates.

12. Means for way-billing express shipments, including a way-bill having distinctively numbered spaces for entries designating the respective shipments, and series of separable adhesive labels applicable to respective shipments, distinctively classified and designated in accordance with the rate 25 of charge and individually distinctively numbered in correspondence with numbers on the way-bill designating the respective shipments.

In testimony whereof, I have hereunto signed my name at Philadelphia, Pennsylvania, this tenth day of July, 1912.
